The Hydraulic Development Corp., Inc., Wil-
mington, Del., a corporation of Delaware

Application August 2, 1940, Serial No. 349,970

7 Claims. (Cl. 113—45)

This invention relates to presses, and in particular to hydraulic presses having a cushioning cylinder piston assembly for supporting the work piece to be shaped and a blankholder for clamping the work piece against a support during the shaping operation.

With hydraulic presses of the above type it sometimes occurs that on the retraction stroke of the press platen, when the work piece is still clamped on its support by the blankholder, the cushioning piston suddenly jumps up and ruins the work piece. The reason for this phenomenon consists in that as long as the work piece is held down by the blankholder platen, the oil beneath the die cushion ram is under high pressure, and while oil is only slightly compressible, yet there is a tendency of the oil to expand with a jerk when the pressure on the oil is suddenly released.

Accordingly it is an object of the invention to provide a hydraulic press of the type referred to, which will eliminate the drawback set forth above.

It is another object of the invention to provide a hydraulic press having a cushioning cylinder and a blankholder, in which the hydraulic pressure beneath the cushioning piston is released in response to the initiation of the retraction stroke of the press platen.

It is a further object of the invention to provide a hydraulic press having a cushioning cylinder and a blankholder platen in which the release of the hydraulic pressure beneath the blankholder platen is effected in response to a predetermined pressure acting upon the press platen.

Still another object of the invention consists in the provision of a hydraulic press of the character set forth in the preceding paragraph in which the rate of the release of the hydraulic pressure is variable.

These and other objects and advantages of the invention will appear more clearly from the following specification in connection with the accompanying drawings, in which:

Figure 1 is a diagrammatic view, mainly in section, showing the working elements of a hydraulic metal drawing press circuit arranged according to this invention, with the upper portion of the press frame work omitted to show the construction more clearly.

Figure 2 shows on a somewhat larger scale, the lower portion of Figure 1 with the valves in section.

General arrangement

According to the present invention, the cushioning cylinder piston assembly is provided with a hydraulic circuit comprising a relief valve which at the time when the press is operated for starting its retraction stroke is actuated so as to release the oil pressure acting beneath the cushioning piston. More specifically, a tonnage control valve, which in response to a predetermined pressure acting upon the press platen causes the initiation of the retraction stroke of the press platen, establishes a communication between fluid under pressure and a shiftable valve which due to this fluid pressure is operated so as to effect communication between that portion of the cushioning cylinder which is beneath the cushioning piston and an exhaust.

Structural arrangement

Referring to the drawings in detail, the hydraulic metal drawing press of Figure 1 comprises a base member 10 connected to a top member 11 (reduced in size for clearness of showing) by means of tie rods 12, the latter being secured in position by means of the nuts 13 upon the ends thereof. Provided in the base member 10 is a bore 14 guiding a supporting member 15 carrying supporting pins 16 for supporting the work piece to be drawn. The pins 16 pass through corresponding openings in the bolster plate 17 which is connected in any convenient manner with the base member 10 and is adapted to receive a die. The supporting member 15 is connected with a piston rod 18 carrying on its lower end a cushioning piston 19 reciprocably mounted in the cushioning cylinder 20. The cushioning cylinder 20 has a port 21 communicating with a conduit 22 which in its turn communicates with a check valve 23. The check valve 23 has a bore 24 normally closed by a ball 25. When the ball 25 is lifted the conduit 22 is adapted to communicate with the conduit 26 leading from the check valve 23 to a shutoff valve 27. The shutoff valve 27 comprises a valve bore 28 adapted to be closed by a valve member 29 operable by means of the threaded shaft 30 and the hand wheel 31 connected thereto. When the valve member 29 is in its open position the valve bore 28 communicates with the conduit 32 leading to a two-way valve 33. The two-way valve 33 comprises a cylinder bore 34 having reciprocably mounted therein a valve member generally designated 35 which comprises two pistons 36 and 37 interconnected by a valve member portion 38 of smaller

diameter than the pistons 36 and 37. The valve member 35 is connected by means of a shaft 39 passing through a bore 40 of the valve 33 with a push rod 41. The valve 33 is closed at its bottom and top by closure members 42 and 43 and a packing 44. The valve 33 furthermore comprises an annular recess 45 communicating with a conduit 46. Branching off from the conduit 46 is a conduit 47 leading through a choke valve 48 to the port 49 of a pilot operated valve generally designated 50. The valve 50 has a reciprocable valve member 51 with two interconnected pistons 52 and 53 reciprocably mounted in the valve bore 54. Also communicating with the valve bore 54 is a conduit 55 leading to a choke valve 56. The pilot operated valve 50 furthermore comprises a recess 57 communicating with a conduit 58 leading to a conduit 59 which in its turn communicates on one hand with the port 60 of the check valve 23 and on the other hand with the port 61 of a relief valve generally designated 62. The relief valve 62 comprises a casing 63 housing a spring 64 the upper end of which engages a plunger 65 which is adjustable so as to vary the thrust of the spring 64, while the other end of the spring 64 engages a plunger 66 with a piston rod 67. The piston rod 67 is reciprocably mounted in the bore 68 and adapted in response to a predetermined pressure in the conduit 59 to be lifted against the thrust of the spring 64 so as to effect communication between the conduit 58 and a recess 69 in the valve 62, which recess communicates through conduit 70 with the conduit 71 leading to the port 72 of a tonnage control valve generally designated 73. The tonnage control valve 73 comprises a casing 74 with a bore 75 in which is reciprocably mounted a plunger 76. The plunger 76 is connected with a cam 77 normally urged downwardly by a spring 78 and adapted when moving upwardly to actuate a lever 79 so as to break a circuit comprising a solenoid 80. The spring 78 is adjustable by means of the threaded shaft 134 so as to vary the thrust of the spring. The interior of the casing 74 communicates with a conduit 82 one end of which is connected with a choke valve 56 while the other end of the conduit 82 is connected with a port 83 of a check valve 84. The port 83 is normally closed by a ball 85 which in its elevated position allows communication between the conduit 82 and a conduit 86 communicating with the conduit 71.

The pilot operated valve 50 has a further port 87 communicating with a conduit 88 from which branches off a conduit 89. The conduit 89 communicates with a conduit 90 leading to the upper portion of the cushioning cylinder 20 and communicating with a conduit 91 leading to a safety valve 92 which is adapted to effect communication between the conduit 22 and the conduit 91. Also communicating with the conduit 90 is a conduit 93 communicating with the interior of the casing 63 of the relief valve 62. Branching off from the conduit 59 is a conduit 94 leading to a pressure indicating gauge 95.

The conduit 46 communicating with the annular recess 45 of the two-way valve 33 leads to a conduit 106 communicating on one hand with a four-way valve 96 and on the other hand with the lower portion of the main cylinder 97. The main cylinder 97 has reciprocably mounted therein a double acting piston head 98 of the drawing plunger 99. The cylinder 97 is furthermore provided with an upper port 100 communicating

with a conduit 101 leading to the four-way valve 96. The four-way valve 96 communicates through a conduit 102 with a variable delivery pump 103 which has its suction side connected through conduit 104 with the surge tank 105 supported by the top member 11 of the press. The conduits 101 and 106 are adapted to supply pressure fluid to the cylinder 97 to advance or retract the drawing plunger 99 according to the position into which the four-way valve 96 has been moved. This valve 96 is of any suitable type known to those skilled in the art and its details form no part of the present invention. According to the present arrangement the valve 96 is normally urged by a spring 135 into such a position as to establish communication between the conduit 102 and the conduit 106 so as to cause the pressure fluid delivered by the pump to effect a retraction stroke of the plunger 99. When the solenoid 80 is energized it shifts the valve 96 against the thrust of the spring 135 to a position in which communication is effected between the conduit 102 and the conduit 101 thereby causing the pressure fluid delivered by the pump 103 to effect an advancing stroke of the plunger 99. Discharge line 107 also connected to the four-way valve 96 leads to the interior of the surge tank 105.

The main cylinder 97 is supplied near the mouth of its cylinder bore 108 with a packing ring 109 beyond which is a packing 110 adapted to be compressed by a gland 111 so as to prevent leakage around the drawing plunger 99. Connected to the drawing plunger 99 is the platen 112, within which are arranged the clamping cylinders 113 having clamping plungers 114 operating therein. Each clamping plunger 114 is provided with a packing 115 and gland 116 for the prevention of leakage. Secured to the platen 112 is a drawing punch 117 adapted to pass through an aperture 118 in the clamping member or blankholder 119 secured to the outer ends of the clamping plungers 114. The extent to which the clamping member 119 may move relative to the platen 112 is limited by the rods 136 connected with the clamping member 119 and provided with nuts 137 on the opposite ends thereof which are adapted to engage the platen 112.

Each of the clamping cylinders 113 communicates with a fluid passageway 120 leading by way of an outwardly opening check valve 121 to a common passageway 122 which extends upwardly through the drawing plunger 99 and opens into the drawing cylinder bore 108 immediately beneath the drawing piston head 98. Consequently, fluid is free to pass from the pull-back or return side of the drawing piston head 98 into the clamping cylinders 113, but is prevented from passing in the opposite direction by the action of the check valves 121. Also passing outwardly from each clamping cylinder 113 is a fluid passageway 123 leading to an intermediate portion of a pipe 124 having on one end a safety valve 125 and on the other hand a pressure relief valve 126. Leading from the discharge side of the safety valve 125 is a discharge line 127 connected to the discharge side of the relief valve 126 by the line 128.

The discharge line 127 passes upwardly into the telescoping cylinder 129, thereby forming a slip connection, enabling the telescoping cylinder 129 and the discharge line 127 to move vertically relatively to each other, an action which necessarily occurs when the platen 112 moves downwardly in response to the action of the drawing

plunger 99. A discharge line 130 leads from the telescoping cylinder 129 into the interior of the surge tank 105 and serves to discharge fluid expelled from the pressure relief valve 126 or the safety valve 125. The safety valve 125 is provided merely as an additional safety feature in the event of a jamming or other failure of the pressure relief valve 126, and is set at a higher pressure than the relief valve 126 so as to operate in case of the accumulation of a dangerous pressure within the corresponding clamping cylinder 113 and a failure of the corresponding pressure relief valve 126 to act. Each clamping cylinder 113 is provided with its own pressure relief valve 126 and safety valve 125 so that a different pressure release point may be given to each clamping cylinder. The pressure relief valves 126 are connected to the drawing plunger passageway 122 by conduits 131 for the purpose of counteracting the action of the relief valves 126 during the return stroke of the drawing plunger 99.

The relief valve 126 does not form a part of the present invention and may be of any convenient type. Preferably a relief valve of the type described in Patent No. 2,167,941 to Walter Ernst may be used.

The conduit 88 communicating with the port 87 of the pilot operated valve 50 leads to the surge tank 105. The conduit 71 communicating with the port 72 of the tonnage control valve 73 communicates with the conduit 101 leading to the upper portion of the cylinder bore 108 of the press.

The push rod 41 connected by shaft 39 with the valve member 35 of the two-way valve 33 has adjustably connected therewith a collar 132 which is adapted to be engaged by the platen arm 133 connected to the platen 112. When the collar 132 is engaged by the upwardly moving platen arm 133 the valve member 35 will be lifted upwardly. The push rod 41 has furthermore adjusted thereon a collar 138 which when the platen nears the limit of its downward stroke is engaged by the platen arm 133 thereby shifting the valve member 35 downwardly so as to interrupt communication between the conduits 32 and 46.

Operation

Assuming that all parts of the press occupy the position shown in Figure 1 which corresponds to the end of the retraction stroke, and that it is now desired to carry out a pressing operation, the pump 103 is started in any convenient manner and shifted to full stroke delivery position. Furthermore, the circuit comprising the solenoid 80 is energized so that the four-way valve 96 is shifted against the thrust of the spring 135 into a position in which communication between the conduit 102 and the conduit 101 is established. Pressure fluid is then delivered by the pump 103 through the valve 96 and the conduit 101 into the space above the piston head 98. This fluid forces the drawing plunger 99 and the platen 112 downwardly, carrying with them the clamping member 119. When the latter engages the periphery of the work piece it comes to a standstill whereas the platen 112 continues to move downwardly. Due to the relative movement between the press platen 112 and the clamping member 119 with its clamping plungers 114 pressure builds up in the clamping cylinders 113 thereby causing the clamping member 119 to firmly clamp the work piece against its support. When the pressure within each clamping cylinder reaches the amount for which its corresponding relief valve 126 is set, the latter opens and discharges fluid through the conduit

128 into the discharge line 127 leading to the telescoping cylinder 129 and thence by the line 130 to the surge tank 105. In this manner each clamping plunger 114 may be caused to exert a different force upon the portion of the blank periphery which is engaged by the clamping member 119. As soon as the drawing punch 117 engages the work piece and begins its actual drawing operation, the supporting pins supporting the work piece intermediate its ends are gradually moved downwardly by the punch 117 as the drawing progresses. Since at this time the pilot operated valve 50 is in such position that the communication between the conduit 58 and the conduit 88 is interrupted, the only way in which the oil beneath the cushioning piston 19 can escape from the cushioning cylinder 20 is through the die cushion relief valve 62 or the safety valve 92. The check valve 23 prevents the oil discharged by the downward movement of the piston 19 from returning through the valves 27 and 33. The safety valve 92 is set at the maximum pressure for which the die cushion cylinder 20 is designed and it is intended only to function in case the valve 62 fails to operate. As the cushioning piston 19 is moved downwardly, oil escapes through the conduit 22, port 60, port 61, and from here, since the piston rod 67 is lifted, through the recess 69, conduit 70, conduit 71 and conduit 101 into the main cylinder. Leakage past the plunger 66 of the valve 62 passes through the conduit 93 and the conduits 89 and 88 into the surge tank 105.

As pressure builds up in the main cylinder 97 it is transmitted through the conduit 71 to the tonnage control valve 73. When this pressure reaches a value corresponding to the setting of the tonnage control valve, the plunger 76 of the tonnage control valve 73 is lifted against the thrust of the spring 78 and shifts the lever 79 so that the latter breaks the circuit comprising the solenoid 80 which, as previously mentioned, when energized shifts the four-way valve 96 so as to establish a communication between the pressure side of the pump 103 and the conduit 101. Consequently, the solenoid 80 is now de-energized so that the spring 135 moves the four-way valve 96 into such a position where the communication between the conduit 102 and 101 is broken while communication between conduit 102 and 106 is established. This results in a reversal of the movement of the drawing plunger 99.

Due to the lifting movement of the plunger 76 pertaining to the tonnage control valve 73 also communication between the conduit 71 and the conduit 81 is established, thereby allowing pressure fluid to pass from the conduit 71 through conduits 81 and 82 and through the choke valve 56 and conduit 55 so as to shift the valve member 51 toward the left thereby establishing communication between the conduits 58 and 88. Now the oil slightly compressed beneath the cushioning piston 19 is relieved through the conduits 22, 59, 58, the port 87 of the valve 50 and the conduit 88 to the tank. Consequently, when the blankholder 119 during the retraction stroke of the press platen releases the work piece, the cushioning piston 19 cannot push the work piece upwardly due to the expansion of oil trapped beneath the cushioning piston 19. The press is now on its retraction stroke. As soon as pressure builds up in the push-back line, pressure fluid passes through conduits 46 and 47 and shifts the reciprocable valve member 51 back to the right so that the communication between the

conduit 88 and the conduit 58 is again interrupted. At the same time oil in the right cavity 139 of the valve 50 is exhausted through the choke valve 56, check valve 84, conduit 71, conduit 101 and discharge line 107 into the tank 105. The function of the check valve 84 is to permit this exhaust but to prevent pressure in the conduit 86 to be conveyed to the conduit 82 when the conduit 86 is under pressure. The purpose of the choke valves 48 and 56 at each 10 end of the pilot operated valve 50 is to prevent the too sudden operation of this valve.

Since during the first portion of the retraction stroke the valve member 35 is in its lowermost position so that the conduit 46 does not communicate with the conduit 32 no pressure fluid can be conveyed through conduit 26 beneath the cushioning piston 19. However, when the platen 112 has almost reached the end of its retraction stroke, the platen arm 133 engages the collar 132 so as to lift the valve member 35 and establish communication between the conduits 46 and the conduit 32. Now pressure fluid is passed through conduit 46, communicating with the pressure side of the pump 103, to the conduit 26 so that the check valve ball 25 is lifted and the pressure in the conduit 26 conveyed beneath the cushioning piston 19 thereby lifting the latter to its initial position. When the platen 112 has reached the end of its retraction stroke, the pump 103 is moved to its neutral position by any convenient means well known to those skilled in the art, for instance, by causing the platen 112 or an arm connected therewith to shift the flow control member of the variable delivery pump 103 to neutral or no delivery position. In case a constant delivery pump is used instead of the variable delivery pump 103 valve means may be provided which at the end of the retraction stroke are actuated in response to the movement of the platen so as to by-pass the delivery of the pump into the tank 105. The press is now ready for a new cycle.

It will be understood that I desire to comprehend within my invention such modifications as come within the scope of the claims and the invention.

Having now fully described my invention what I claim as new and desire to secure by Letters Patent, is:

1. A hydraulic press comprising in combination, a press ram and main cylinder, hydraulic motor means for reciprocating said ram, hydraulically operable cushioning means, means adapted to supply pressure fluid to said motor means and said cushioning means for actuating the same, fluid operable means controlling the initiation of the retraction stroke of said ram and being responsive to a predetermined fluid pressure within said main cylinder exerted by said motor means on the work piece to be shaped during the pressing operation for initiating the retraction stroke of said ram, and valve means operatively connected with said fluid operable means and adapted in response to the pressure within said main cylinder to release fluid pressure on said cushioning means.

2. A hydraulic press comprising in combination a press ram having associated therewith fluid operable advancing and retracting means, clamping means for clamping a work piece against a support, means for actuating said clamping means, a fluid operable cushioning cylinder-piston-assembly adapted to support por-

tions of said work piece while it is being shaped, means for supplying pressure fluid to said advancing and retracting means and to said cylinder-piston-assembly for actuating the same, control means responsive to a predetermined pressure on said advancing means for releasing pressure fluid therefrom, and valve means normally preventing hydraulic communication between said cushioning cylinder-piston-assembly and an exhaust and being operable in response to the release of pressure fluid by said control means for causing communication of said cushioning cylinder-piston-assembly with said exhaust.

3. In a hydraulic press, a reciprocable press ram, clamping means associated with said ram for holding a work piece during the pressing operation, fluid operable cushioning means for supporting portions of the work piece while it is being drawn, a fluid source adapted to supply pressure fluid to said ram and said cushioning means, controlling means associated with said fluid source for directing pressure fluid from said fluid source to said ram and said cushioning means so as selectively to effect an advancing stroke and a retraction stroke thereof, and fluid pressure responsive means adapted in response to a predetermined pressure on said ram to actuate said controlling means for initiating the retraction stroke of said ram and also adapted to cause release of pressure fluid from said cushioning means.

4. In a hydraulic press, a press platen, clamping means associated with said platen for holding a work piece during the shaping operation thereof, hydraulically operable cushioning means for supporting portions of the work piece while it is being drawn, a fluid source adapted to supply pressure fluid to said ram and said cushioning means for actuating the same, pilot valve means operable independently of the travel of said platen to release pressure fluid from said cushioning means while the latter engages the work piece, and means adapted at the end of the pressing operation to cause actuation of said pilot valve means for releasing pressure fluid from said cushioning means.

5. In combination in a hydraulic press, a fluid operable press ram having an advancing side and a retraction side, clamping means associated with said ram for holding a work piece while it is being shaped, a fluid operable cushioning cylinder piston assembly for supporting portions of the work piece during the pressing operation, a variable delivery pump for supplying pressure fluid to said ram and said cushioning piston, electrically operable means for controlling the supply of pressure fluid from said pump selectively to the advancing or retraction side of said ram, fluid pressure operable means adapted in response to a predetermined pressure exerted by said pump on said ram to control the energization of said electrically operable means so as to cause said pump to deliver fluid to the retraction side of said ram, pilot valve means responsive to the operation of said pressure responsive means for releasing pressure fluid from said cushioning cylinder piston assembly, and means responsive to a predetermined pressure on said ram for reducing fluid pressure to said cushioning means.

6. In a hydraulic press, a fluid operable press ram, clamping means associated with said ram for holding a work piece in clamped position during the pressing operation, fluid operable

cushioning means adapted to support portions of the work piece while it is being drawn, a fluid source for supplying pressure fluid to said ram and said cushioning means, fluid pressure responsive means operable by a predetermined fluid pressure acting on said ram for causing initiation of the retraction stroke of said ram, pilot valve means operable independently of the travel of said ram and adapted in response to the operation of said pressure responsive to release pressure fluid from said cushioning means, and adjustable means for varying the rate of operation of said pilot valve means.

7. In a hydraulic press, a press ram having associated therewith fluid operable advancing and retracting means for actuating the same, clamping means for holding a work piece in clamped

position while it is being drawn, means for actuating said clamping means, a hydraulically operable cushioning cylinder-piston-assembly for supporting portions of the work piece during the 5 pressing operation, a pressure fluid source for supplying pressure fluid to said ram advancing and retracting means and said cushioning plunger for actuating the same, fluid pressure responsive means responsive to a predetermined 10 fluid pressure on said ram advancing means for initiating a reverse movement of said ram, and means operable by pressure fluid controlled by 15 said pressure responsive means for releasing pressure fluid from said cushioning cylinder-piston-assembly.

WALTER ERNST.
